UNITED STATES PATENT OFFICE

140,877

DESIGN FOR A COMPACT

Vincent C. Le Sage, Los Angeles, Calif., assignor to Royal Plastic Company, Los Angeles, Calif., a partnership

Application January 25, 1945, Serial No. 117,591

Term of patent 14 years

(Cl. D86—10)

To all whom it may concern:

Be it known that I, Vincent C. Le Sage, a citizen of the United States of America, residing in the city of Los Angeles, in the county of Los Angeles, State of California, have invented a new, original, and ornamental Design for a Compact, of which the following is a specification, reference being had to the accompanying drawings, forming a part thereof.

Fig. 1 is a top plan view of a compact in closed position, showing my new design;

Fig. 2 is a front elevational view of the same;

Fig. 3 is a side elevational view; and

Fig. 4 is a frontal perspective view of the compact in open position.

I claim:

The ornamental design for a compact, substantially as shown.

VINCENT C. LE SAGE.
